(57) **CLAIM**

The ornamental design for a mouth plug for container, as shown and described.

DESCRIPTION

FIG. 1 is a front perspective view of a mouth plug for container according to our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed lines in the drawings depict environmental subject matter only and form no part of the claimed design. The long dash-short dash-long dash lines form boundary portions and form no part of the claimed design.
